UNITED STATES PATENT OFFICE

PETER J. PARLATO, OF ELMHURST, AND ARTHUR R. KRAUSE, OF WOODHAVEN,
NEW YORK

DESIGN FOR A LIGHTING FIXTURE

Application filed March 9, 1933. Serial No. 47,422. Term of patent 3½ years.

To all whom it may concern:

Be it known that we, PETER J. PARLATO and ARTHUR R. KRAUSE, both citizens of the United States, and residing respectively at 5131 Manila Street, Elmhurst, in the county of Queens, city and State of New York, and at 9104 91st Avenue, Woodhaven, in the county of Queens, city and State of New York, have invented a new, original, and ornamental Design for Lighting Fixtures, of which the following is a specification, reference being had to the accompanying drawing forming part thereof.

Fig. 1 is a perspective view of a lighting fixture showing applicants' new design.

Fig. 2 is an elevation partly in section

through the lighting fixture to illustrate the spacing of the reflectors and the partial parabola and a transparent disk.

The design is embodied in a lighting fixture as shown and comprises separate metal reflectors held together by metal straps and lying in substantially horizontal planes, the metal reflectors being so formed as to make a partial parabola, the bottom reflector terminating with an opening which is covered by a transparent material.

We claim:—

The ornamental design for a lighting fixture as shown and described.

PETER J. PARLATO.
ARTHUR R. KRAUSE.
